United States Patent Office.

L. J. ADAMS, OF HOOSICK FALLS, NEW YORK, ASSIGNOR TO HIMSELF, WILLIAM HYLAND, AND A. B. MILLER, OF SAME PLACE.

Letters Patent No. 96,181, dated October 26, 1869.

IMPROVED CLOTHES-DRIER.

The Schedule referred to in these Letters Patent and making part of the same

To all whom it may concern:

Be it known that I, L. J. ADAMS, of Hoosick Falls, county of Rensselaer, and State of New York, have invented a new and useful Improvement in Clothes-Bars; and I do hereby declare that the following is a full, clear, and exact description thereof, which will enable others skilled in the art to make and use the same, reference being had to the accompanying drawing, forming part of this specification.

This invention relates to improvements in the construction of that class of clothes-bars made in frames or panels, and hinged together, so as to swing open on the hinge-joints horizontally, when standing on one end.

The invention consists in a peculiar way of hinging the said frames or panels to a common centre, so that when extended, they will all radiate from a common centre, instead of assuming a zigzag or serpentine line.

Figure 1 represents a side elevation of my improved clothes-frame, in the closed position; and

Figure 2 represents a top view of the same.

Similar letters of reference indicate corresponding parts.

I make one frame or panel of two posts A B, and cross-bars C, arranged in pairs, and of two or more pairs, and the other frames I make of one post, D, and

single cross-bars E', the latter preferably a little shorter than the bars C.

The ends of the bars E, not provided with a post, I pivot between the bars C, close to the post A, by bolts or pins F, passing through the bars C and the said bars E.

By another arrangement, I may enlarge the ends of the bars E, and pass the post A through holes therein, using that as the pivot or axis of the said bars E, which, in this case, I would make longer than the bars C.

This arrangement makes a strong, simple, and desirable clothes-frame, which will open around a common centre, and occupy less available room than the common arrangement.

Having thus described my invention,

What I claim as new, and desire to secure by Letters Patent, is—

The combination, with the panel or frame, composed of the posts A B and bars C, arranged in pairs, of the frames, consisting of the posts D and bars C, when the said bars D are pivoted between the bars C, either to bolts F or the posts A, substantially as specified.

L. J. ADAMS.
